(57) **CLAIM**

The ornamental design for a combined toolbox and vacuum cleaner, as shown and described.

DESCRIPTION

FIG. 1 is a front, top, and side view of a combined toolbox and vacuum cleaner that has the design.

FIG. 2 is an elevation view of the front of the product.

FIG. 3 is an elevation view of the vacuum side of the product.

FIG. 4 is an elevation view of the toolbox side of the product.

FIG. 5 is an elevation view of the rear of the product.

FIG. 6 is a top view of the product.

FIG. 7 is a bottom view of the product.

FIG. 8 is a front, top and side view of the vacuum part of the product.

FIG. 9 is an elevation view of the front of the vacuum part of the product.

FIG. 10 is an elevation view of an outer end of the vacuum part of the product.

FIG. 11 is an elevation view of the mating end of the vacuum part of the product.

FIG. 12 is an elevation view of the rear of the vacuum part of the product.

FIG. 13 is a top view of the vacuum part of the product.

FIG. 14 is a bottom view of the vacuum part of the product.

FIG. 15 is front, top and side view of the toolbox part of the product.

FIG. 16 is a view of the toolbox part of the product, with the lid opened.

FIG. 17 is a view of the toolbox part of the product, with the lid opened and the tray removed.

FIG. 18 is an elevation view of the front of the toolbox part of the product.

FIG. 19 is an elevation view of one end of the toolbox part of the product.

FIG. 20 is an elevation view of the opposite end of the toolbox part of the product.

FIG. 21 is an elevation view of the rear of the toolbox part of the product.

FIG. 22 is a top view of the toolbox part of the product; and, FIG. 23 is a bottom view of the toolbox part of the product. The broken lines shown in the drawings illustrate portions of the combination toolbox and vacuum cleaner and form no part of the claimed design.
